CLAIM

The ornamental design for a power converter, as shown and described.

DESCRIPTION

FIG. 1 is perspective view of a power converter showing my design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines are used to show unclaimed environment, and thus form no part of the claimed design.

1 Claim, 7 Drawing Sheets(56)
